UNITED STATES PATENT OFFICE.

PEARL M. BURGESS, OF READING, MASSACHUSETTS, ASSIGNOR TO PEARL M. BURGESS AND JOSEPH BLACHER, DOING BUSINESS AS BURGESS AND BLACHER, OF BOSTON, MASSACHUSETTS, A FIRM.

HOSPITAL WINDOW.

Application filed June 14, 1922. Serial No. 568,283.

To all whom it may concern:

Be it known that I, PEARL M. BURGESS, a citizen of the United States, residing at Reading, in the county of Middlesex and State 5 of Massachusetts, have invented new and useful Improvements in Hospital Windows, of which the following is a specification.

This invention relates to windows of rooms in which the maintenance of a uniform degree of temperature is important, as in hospitals, such windows including inner and outer glazed sashes separated by air spaces.

The chief object of the invention is to check the transmission of heat from the room 15 through the inner sash into the air space between the sashes, and to prevent the formation of frost on the glass of the sashes, and particularly that of the inner sash.

The invention is embodied in the improvements hereinafter described and claimed.

Of the accompanying drawings forming a part of this specification,—

Figure 1 is a side view of a hospital window embodying the invention, looking toward the outer side of the outer sash.

Figure 2 is a section on line 2—2 of Figure 1, and a plan view of parts below said line.

Figure 3 is a fragmentary section on line 3—3 of Figure 1, looking toward the left.

The same reference characters indicate the same parts in all of the Figures.

12 designates the outer sash, and 13 the inner sash of a hospital window, these being separated by an air space 14. The glass 35 elements of the outer sash are designated by 12^a, and those of the inner sash by 13^a.

I provide air-heating means located in the lower portion of the air space 14, midway between and spaced from the vertical edges 40 of the air space, said means being preferably embodied in an electrical resistance unit 15, fixed to the sill 16 between the sashes. Said unit, which is shown somewhat conventionally, preferably has a flat-sided elongated body mounted on ears or brackets 18, fixed to the sill and supporting the body above the sill with its flat sides facing upward and downward. I do not limit myself, however, to a unit thus characterized.

50 The electrical connections (not shown) may be arranged in any suitable manner.

Outside air is admitted to the lower portion of the air space below the heating means by lower inlet ducts 20, arranged to cause the

entering air to impinge upon, and be 55 warmed by, the heating means. The inlet ducts are also located midway between and spaced from the vertical edges of the air space. The warmed air rises in the air space to upper outlet ducts 21, communicating with the upper portion of the air space and located relatively near the vertical edges of said space, out of vertical alinement with the inlet ducts, the arrangement being such that an upward current of warm or tempered 60 air is maintained in the air space in contact with both sashes, and checks transmission of heat from the room through the glass of the inner sash, and prevents the formation of frost on the glass of both sashes. 65

The inlet ducts 20 are preferably formed in the sill 16, said ducts having intake ends in the outer edge or face of the sill, and discharge ends in the upper surface of the sill between the sashes, the ducts being inclined 70 upwardly from their intake to their discharge ends, to prevent rain or snow from passing through the ducts.

The outlet ducts 21 are preferably formed in the top bar of the outer sash, said ducts 75 having hoods 22, formed to prevent the entrance of rain or snow.

To provide for the admission of the warmed air to the room through the inner sash for ventilation, I preferably construct the inner 85 sash with a movable section or sections, adapted to open inwardly. In this instance I show two movable sections 13^b, one at each end of the sash. Each section preferably extends from the bottom to the top of the 90 sash, so that when either section is opened air may pass from the upper portion of the air space into the room. The sections 13^b are connected with fixed members of the inner sash by hinges at 23 (Figure 2), arranged to 95 permit the section to swing on vertical axis.

The outer sash may include movable sections 12^b, connected by hinges at 24 with fixed members of the outer sash. The sections 12^b are preferably of about half the 100 height of the outer sash, as shown by Figure 1.

I do not limit myself to electrical heating means, although I consider the same preferable. Heating means utilizing steam or other fluid may be employed if desired.

As shown by Figure 1, the number of the lower ducts 20 exceeds that of the upper

ducts 21, five lower ducts and two upper ducts being shown. The capacity of the lower ducts is, therefore, greater than that of the upper ducts. The upper ducts, therefore, collectively constitute a vent means, so retarding the escape of air from the upper portion of the air space, that the admitted air, warmed by the heater, is distributed laterally while flowing upward, and is caused to contact with all portions of the opposed faces of the sashes, and flow slowly through the air space, so that its heat is fully utilized to prevent the formation of frost.

15 The heater and the inlet ducts 20 are preferably located at the center of the lower portion of the air space, while the upper, or vent ducts 21, are preferably located at the ends of the upper portion of the air space, and out of vertical alinement with the inlet ducts, the ducts 20 being arranged to cause all of the admitted air to impinge directly on the heater. This relative arrangement of the ducts facilitates 25 the warming of the admitted air, and facilitates the distribution of the ascending warmed air, by causing the air in flowing from the ducts 20 to the ducts 21, to flow also outward from the central portion to the end portions of the air space.

30 The provision of means as described for causing a lateral flow of the warmed air and its contact with all portions of the opposed faces of the sashes, enables a relative-

ly small and economically maintained heater to effectively warm the admitted air which, owing to its slow movement, communicates the greater portion of its heat to the sashes before escaping at the vent ducts.

35 In case it is desired to utilize the air admitted to the air space, for ventilating the room, this may be accomplished by opening the sash sections 13^b sufficiently to form air passages of much greater capacity than the vent ducts 21. When this is done, the greater portion, if not all, of the admitted air will enter the rooms, any possible escape of air through the vent ducts being so small as to be negligible, so far as ventilation is concerned.

40 45 I claim:

A hospital window comprising, in combination, glazed inner and outer sashes, separated by an air space, inlet ducts communicating with the bottom portion of said space midway between, and spaced from, the vertical edges thereof, outlet ducts communicating with the upper portion of the air space, and a heater located in the lower portion of the air space midway between, and spaced from, the vertical edges thereof and in the path of air admitted by the inlet ducts, the outlet ducts being relatively near said vertical edges, so that they are out of vertical alinement with the inlet ducts.

50 55 60 In testimony whereof I have affixed my signature.

PEARL M. BURGESS.
